DRILL COLLAR FOR DRILLING STRINGS

Jesse C. Wright, Los Angeles, Calif.

Application November 14, 1936, Serial No. 110,820

18 Claims. (Cl. 255—28)

This invention relates to rotary well drilling equipment and relates more particularly to a drill collar for use in a rotary well drilling string. A general object of this invention is to provide a practical, effective, heavy weight drill collar embodying novel, dependable means for flushing the drilling tool and the drill collar free in the event they become caught or sanded in the well bore.

Another object of this invention is to provide improvements in drill collars of the general character described and claimed in Letters Patent No. 2,090,822 entitled Drill collar, granted to me August 24, 1937.

A drill collar is an elongate rigid member usually provided in a well drilling string immediately above the drilling tool to lend rigidity to the lower portion of the string and to feed the drilling tool into the earth formation through its weight. It is often necessary to employ a drill collar of great weight to impose a heave feed pressure on the drilling tool. Heretofore it has been deemed necessary to leave a substantial annular space around the drill collar to permit a wash-over pipe to be passed over it in the event the drilling string parts or the tools become caught in the well. Because of this factor it has been deemed impractical to increase the diameter of a drill collar to increase its weight and it has been the usual practice to employ a very long drill collar when a drill collar of great weight is necessary. A very long drill collar is impractical as its upper portion has a tendency to fall over against the wall of the well bore and cause the drill to make a crooked or inclined bore.

Another object of this invention is to provide a drill collar of large external diameter and, therefore, of great weight and minimum length that may be employed without danger of becoming lost or permanently sanded in the well bore.

Another object of this invention is to provide a drill collar of large diameter that embodies novel effective means for discharging flushing fluid to flow upwardly around its periphery and free it of accumulations of sand and mud in the event it becomes mudded in the well bore, making it unnecessary to lower a wash pipe downwardly over the drill collar.

Another object of this invention is to provide a drill collar of the character mentioned embodying a movable part adapted to be manipulated by a wash-over pipe or the like to impart jarring blows to the drill collar.

Another object of this invention is to provide a drill collar of the character mentioned embody-

ing an effective fluid handling means adapted to receive flushing fluid from a wash-over pipe and operable to discharge the fluid in a manner to assure the removal of accumulations of sand and mud from around the drill collar.

Another object of this invention is to provide a drill collar of the character mentioned embodying valve means for discharging the flushing fluid into the well at progressively lower points in the event that the lower portion of the drill collar is so tightly mudded in that the fluid cannot escape from its lower end portion.

A further object of this invention is to provide a drill collar of the character mentioned that is sufficiently large in external diameter to form an effective guide bearing and stabilizer for the drilling string and the drilling tools.

The various objects and features of my invention will be fully understood from the following detailed description of a typical preferred form and application of the invention, throughout which description reference is made to the accompanying drawing, in which:

Fig. 1 is a central longitudinal detailed sectional view of the drill collar provided by this invention showing the valve tube in its normal position and illustrating the body in side elevation. Fig. 2 is a view similar to Fig. 1 showing the valve tube in a raised position and Figs. 3, 4 and 5 are enlarged transverse detailed sectional views taken as indicated by lines 3—3, 4—4 and 5—5, respectively, on Fig. 1.

The improved drill collar of this invention includes, generally, a body 10 to be connected in a rotary well drilling string, a ported tubular member 11 surrounding the body 10 with clearance, and a shiftable valve tube 12 surrounding the body 10 within the member 11 for receiving flushing fluid from a wash-over pipe P.

The body 10 may be similar to a typical drill collar and a typical collar of suitable diameter may be employed as the body of the device. The body 10 is an elongate member or structure of steel having a thick wall to be of substantial weight. In practice the body 10 may be made up of one or more lengths or sections. The body 10 is preferably cylindrical and of uniform external diameter, as illustrated in the drawing. The upper end of the body 10 is intended to be connected with the lower end of a rotary well drilling string S. In the arrangement illustrated a sub 13 connects the upper end of the body 10 with the lower end of the drilling string S. The sub 13 is provided with circumferentially spaced abutments or projections 14 for the pur-

pose to be hereinafter described. A special sub 15 is secured to the lower end of the body 10. The sub 15 may have a pin threaded in a tapered socket 16 in the lower end of the body 10. The 5 sub 15 is larger in diameter than the body 10 and is stepped to present two upwardly facing annular shoulders 17 and 18. A suitable drilling tool T may be connected with the lower end of the sub 15. In accordance with the invention 10 the body 10 has a central longitudinal fluid passage 20 extending through it from one end to the other to conduct the circulation fluid employed during the drilling operation.

The tubular member 11 surrounds the body 15 10 and is connected with the sub 15 to be rigid with the body. The tubular member 11 may be a simple tube threaded on the sub 15 to have its lower end bear on the shoulder 18. The member 11 extends upwardly from the sub 15 to surround 20 the body 10 for a substantial portion of its length. The member 11 is cylindrical and is sufficiently large in internal diameter to surround the body 10 with substantial clearance. Due to its length and diameter the member 11 25 is of substantial weight to materially add to the weight of the drill collar. The tubular member 11 forms the relatively stationary element of the valve means of the invention and is provided with a multiplicity of vertically spaced ports 21. 30 The ports 21 are preferably distributed throughout a substantial portion of the length of the member 11. The sub 15 is preferably provided with fluid discharge ports 22 extending downwardly and outwardly from its shoulder 17 to its 35 exterior. It will be observed that the tubular member 11 is considerably larger in diameter than the drill collar body 10 so that it is adapted to cooperate with the side wall of the well bore to form a bearing for guiding and stabilizing 40 the string S and the drilling tool.

The valve tube 12 shiftably extends between the body 10 and the surrounding tubular member 11. The valve tube 12 surrounds the body 10 with substantial clearance leaving a longitudinal fluid passage 23. The lower end of the fluid passage 23 communicates with the ports 22 in the sub 15. The valve tube 12 shiftably or 45 slidably cooperates with the interior of the member 11 to control its ports 21. The lower end of the tube 12 normally rests on the shoulder 17 and the tube is sufficiently long to project upwardly beyond the upper end of the member 11 when supported on the shoulder 17. Due to 50 its length the valve tube 12 is of substantial weight and when resting on the shoulder 17 materially adds to the weight of the drill collar assembly.

The invention preferably provides a releasable clutch means for causing the tube 12 to turn 55 with the body 10 during the rotary drilling and for transmitting rotation from the tube to the body when an attempt is being made to free the drill collar. The clutch means may include circumferentially spaced clutch teeth 24 on the shoulder 17 for cooperating with correspondingly shaped notches 25 on the lower end of the tube 12. When the tube 12 is resting on the shoulder 17 the notches 25 receive the clutch teeth 24 so that a positive rotative drive is provided between the sub 15 and the valve tube 12. 60 The tube 12 may be freed for rotation independently of the body 10 by merely raising it to disengage its notches 25 from the teeth 24.

Means is provided on the upper end of the 75 valve tube 12 for connecting with or receiving a

coupling part on the lower end of the wash pipe P. This means may include a tubular coupling member 26 threaded on the upper end of the tube 12. The particular coupling member 26 5 illustrated has a tapered pin 27 on its upper end provided with a relatively coarse thread. The pin 27 is adapted to be received in a socket 28 in a coupling member 29 on the lower end of the pipe P. The upper end of the pin 27 is adapted to jar upwardly against the projections 10 14 to impart a jarring action to the body 10 and parts connected therewith when the wash pipe P is suddenly moved upwardly as will be herein-after described.

The pin 27 surrounds the body 10 with clearance leaving an annular fluid passage 30 for receiving fluid from the wash pipe P. The interior of the coupling member 26 forms a chamber 31 communicating with the lower end of the passage 30 and with the upper end of the passage 23. A sand trap is provided in the chamber 31 to prevent sand from closing or clogging the passage 23. The sand trap includes vertically spaced partitions or baffles 32. The baffles 32 are in the form of internal flanges on the member 26 closely embracing the body 10 to shiftably 25 guide and steady the valve tube 12. Circumferentially spaced ports 33 are provided in the baffles 32. The ports 33 may be in the form of notches in the inner edges of the baffles 32. The 30 ports 33 are circumferentially offset, that is, the ports 33 of one baffle 32 are circumferentially offset from the ports 33 of the other baffle. The ported baffles 32 extending across the interior of the chamber 31 are adapted to receive any sand 35 or mud that may settle downwardly through the passage 30. The mud and sand collecting on the baffles 32 may bridge across the ports 33 to close them off. These bridges of sand and mud prevent mud or sand from entering the passage 23. 40 The sand and mud accumulated on the baffles 32 is readily washed away when the wash pipe P is connected with the coupling member 26.

In operation the drill collar is connected with the drilling string S as illustrated in the drawing. During the drilling operation the string S is rotated and fed downwardly in the usual manner and the weight of the drill collar is imposed on the tool T to feed it into the earth formation. It will be obvious that the drill collar embodying the heavy walled body 10 and the surrounding member 11 and tube 12 is very heavy to impose a substantial feed pressure on the tool T. The drill collar is of maximum weight and minimum length so that its weight is 55 concentrated immediately above the tool T. Throughout the drilling operation rotary mud or circulation fluid is pumped downwardly through the string S to flow through the passage 20 and discharge from the tool T. The valve tube 12 normally rests on the shoulder 17 and is connected with the body 10 to turn therewith by the teeth 24 cooperating with the notches 25. The outer tube or member 11 is received in the well bore with only slight clearance sufficient for the 60 return flow of the circulation fluid and due to its large diameter may act as a bearing to stabilize and guide the string S and the drilling tool T.

In the event that the drilling string S breaks or parts or the tool T becomes caught or sanded in the well bore the wash-over pipe P may be lowered into the well to pass downwardly over the string in the well. The wash-over pipe is lowered until its socket 28 receives the pin 27 75

whereupon it is turned to thread the coupler 29 on the pin. Circulation fluid or water is pumped downwardly through the pipe P and passes through the passage 30 and the chamber 31 into the passage 23. Any sand that may have accumulated on the baffles 32 is readily washed away by the fluid. The fluid flows downwardly through the passage 23 and may discharge from the ports 22. The fluid thus discharged from the ports 22 is free to flow upwardly around the drill collar to wash away the accumulations of mud and sand. This may free the drill collar so that it may be readily withdrawn from the well together with the tool T on the pipe P.

15 In some instances the sand and mud may be so tightly packed about the lower portion of the drill collar that the circulation fluid or water under pressure cannot discharge from the ports 22. If this occurs the wash pipe P may be raised 20 to uncover certain of the ports 21. Uncovering of the ports 21 of course allows the flushing fluid to discharge into the well. The mud and sand may be so tightly packed about the drill collar that the fluid cannot discharge from the lowermost ports 21 and it may be found necessary to raise the tube 12 to uncover higher ports 21. Thus higher ports 21 may be progressively uncovered until the circulation fluid is freely discharged into the well bore. The fluid discharging from the ports 21 erodes and carries away the accumulations of sand and mud above the uncovered ports 21 has been washed away the tube 12 may be lowered to close such ports and cause 35 the fluid to discharge from the lower ports. In this manner the valve tube 12 may be manipulated to effect the removal of the accumulations of sand and mud from around the drill collar even though such accumulations may be so tightly packed as to prevent the initial discharge of the circulation fluid from the lower ports 21.

It may be found necessary or desirable to impart an upward jarring action to the body 10 and the member 11 to free the drill collar and the tool T. The wash pipe P may be suddenly raised to bring the upper end of the pin 27 into jarring engagement with the projections 14. This operation may be continued until the drill collar is loosened or freed. When the drill collar has been loosened and freed for removal the wash pipe P is raised to bring the upper end of the pin 27 against the projections 14 so that the drill collar and tool connected therewith may be withdrawn from the well on the wash pipe. The drill collar 55 of the present invention is of great weight and minimum length to have its weight concentrated immediately above the drilling tool to cause the tool to drill a straight vertical bore. The drill collar is of large external diameter to act as a guide and bearing. The member 11, the valve tube 12 and the other parts of the means for handling the flushing fluid assure the ready freeing and removal of the drill collar from the well in the event that it becomes caught or sanded 60 in the bore.

Having described only a typical preferred form and application of my invention, I do not wish to be limited or restricted to the specific details herein set forth, but wish to reserve to myself any variations or modifications that may appear to those skilled in the art or fall within the scope 70 of the following claims:

Having described my invention, I claim:

1. A drill collar including, a body to be connected in a drilling string, a ported tubular mem-

ber surrounding and secured to the body, and a valve tube entering the member to supply fluid thereto and shiftable to control its ports.

2. A drill collar including, a body to be connected in a drilling string, a ported tubular member surrounding and secured to the body, a tube entering the member to supply fluid thereto and shiftable to control its ports, and means on the tube for connecting with a wash pipe for supplying fluid to the tube and for shifting the tube. 10

3. A drill collar including, a body to be connected in a drilling string, a ported tubular member surrounding and secured to the body, a tube extending into the member to supply fluid thereto and shiftable to control its ports, and means 15 connecting the tube with the body to turn therewith.

4. A drill collar including, a body to be connected in a drilling string, a ported tubular member surrounding and secured to the body, and a tube 20 surrounding the body with clearance to deliver fluid to the tube and shiftable cooperating with the interior of the member to control its ports.

5. A drill collar including, a body to be connected in a drilling string, a tubular member surrounding the body with clearance and secured to the body, the member having vertically spaced 30 ports, and a tube surrounding the body and extending into the member to supply fluid thereto and shiftable vertically in the member to control said ports.

6. A drill collar including, a body to be connected in a drilling string, a tubular member surrounding the body with clearance and secured to 35 the body, the member having vertically spaced ports, a tube around the body and extending into said member to supply fluid thereto and movable vertically to control the delivery of fluid to said ports, and a connecting member on the upper 40 end of the tube for connecting a pipe with the tube to supply fluid thereto and to move the same.

7. A drill collar including, a body to be connected in a drilling string, a tubular member surrounding the body with clearance and secured to the body, the member having vertically spaced ports, a tube surrounding the body and shiftable in the member to control its ports and to supply fluid to the member, means for connecting a fluid 50 handling pipe with the tube, and releasable clutch means for transmitting rotation between the body and tube. 45

8. A drill collar for use in a well drilling string including, a body to be interposed in the string, a tubular weight element carried by and surrounding the body, the element having a fluid discharge port, a tube shiftable in the element to supply fluid thereto and to control said port, and means for connecting a fluid handling pipe with 60 the tube. 55

9. A drill collar for use in a well drilling string including, a body to be interposed in the string, a tubular weight element carried by and surrounding the body, the element having a fluid discharge 65 port, a tube shiftable in the element to supply fluid thereto and to control said port, and an abutment on the body engageable by the tube when the same is moved longitudinally to impart a jarring action to the body. 70

10. A drill collar for use in a well drilling string including, a body to be interposed in the string, a tubular weight element carried by and surrounding the body, the element having a fluid discharge port, a tube shiftable in the element to supply 75

fluid thereto and to control said port, a coupling member on the upper end of the tube for connecting the same with a pipe for shifting the tube and for supplying fluid thereto, and an abutment on the body engageable by the coupling member to impart a jarring action to the body.

11. A drill collar for use in a well drilling string including, a body to be interposed in the string, a tubular weight element carried by and surrounding the body, the element having a plurality of vertically spaced fluid discharge ports, a tube shiftable in the weight element to supply fluid thereto and to control its ports, and a coupling member on the tube having a thread for mating with a thread on a pipe for manipulating the tube and for supplying fluid thereto.

12. A drill collar for use in a well drilling string including, a body to be interposed in the string, a tubular weight element carried by and surrounding the body, the element having a plurality of vertically spaced fluid discharge ports, a tube shiftable in the weight element to supply fluid thereto and to control its ports, an abutment on the body for limiting the upward movement of the tube thereon, and a coupling member on the tube having a thread for mating with a thread on a pipe for manipulating the tube and for supplying fluid thereto.

13. A drill collar for use in a well drilling string including, a body to be interposed in the string, a sub on the lower end of the body, a tubular member carried by the sub and surrounding the body with clearance, the member having vertically spaced fluid discharge ports, a tube entering the upper end of the member to supply fluid thereto and shiftable to control said ports, the tube being adapted to rest on the sub, and means on the upper end of the tube for mating with a coupler on a pipe for shifting the tube and for supplying fluid thereto.

14. A drill collar for use in a well drilling string including, a body to be interposed in the string, a sub on the lower end of the body, a tubular member carried by the sub and surrounding the body with clearance, the member having vertically spaced fluid discharge ports, a tube enter-

ing the upper end of the member to supply fluid thereto and shiftable to control said ports, the tube being adapted to rest on the sub, cooperating releasable clutch parts on the tube and sub, and means on the upper end of the tube for mating with a coupler on a pipe for shifting the tube and for supplying fluid thereto.

15. A drill collar for use in a well drilling string including, a body to be interposed in the string, a tubular weight element carried by and surrounding the body, the element having a fluid discharge port, a tube shiftable in the element to supply fluid thereto and to control said port, a coupling member on the upper end of the tube for connecting the same with a pipe for shifting the tube and for supplying fluid thereto, a sand trap in the coupling member, and an abutment on the body engageable by the coupling member to impart a jarring action to the body.

16. A drill collar for use in a rotary well drilling string comprising, a body to be connected in the string, a ported tubular member surrounding and secured to the body, and a valve tube telescopically related to the tubular member and shiftable with respect thereto to control its ports.

17. A drill collar for use in a rotary well drilling string comprising, a body to be connected in the string, a ported tubular member surrounding and secured to the body, a valve tube in telescopic relation to the tubular member and shiftable relative to the tubular member to control its ports, and connecting means on the tube for connecting a wash over pipe with the tube for shifting the tube.

18. A drill collar for use in a well drilling string including, two parts, one a body to be interposed in the string, the other a tubular weight element carried by and surrounding the body, the element having a fluid discharge port, a tube in shiftable telescopic relation to the said element to supply fluid thereto and to control said port, and an abutment on one of said parts engageable by the shiftable tube when the same is moved longitudinally to impart a jarring action to the said parts.

JESSE C. WRIGHT.
